DESIGN FOR A DRESS

Albert E. Levy, New York, N. Y.

Application December 23, 1937, Serial No. 73,810

Term of patent 3½ years

To all whom it may concern:

Be it known that I, Albert E. Levy, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

My design is characterized by the button tab on the collar portion of the dress as shown in combination with the buttons on the front portion of the dress.

I claim:

The ornamental design for a dress substantially as shown and described.

ALBERT E. LEVY.
